SASH HANGER

Patrick L. Donovan, Peoria, Ill.

Application March 19, 1947, Serial No. 735,692

2 Claims. (Cl. 16—172)

1

This invention relates to hangers for storm sashes and screens.

An object is to furnish a type of hanger by which a sash or screen may be more readily hung from within a room whose window is to be protected.

Another object is to provide a hanger for attachment to a window frame that will provide for readily guiding into it the eye or link of the hanger carried by the sash or screen to be hung.

Still another object is to provide the hanger portion secured to the window frame with a pair of hooks, one above the other in opposed positions and to locate between them a third upturned hook for finally receiving the eye or link portion of the sash as the seating position of the latter.

Again, an object lies in furnishing a structure in a sash hanger by which the sash cannot be unseated and blown off by the winds when accidentally left unlatched and hanging freely.

Other objects and advantages will appear in the following specification aided by the appended drawing forming part hereof.

Figure 1 is a front elevation of the complete two part assembled hanger structures in one of the positions of a suspended storm sash.

Figure 2 is a transverse section of the window frame showing the hanger portions in the same relation as those in Figure 1, the eye or link portion on the sash being shown in part longitudinal section.

Figure 3 illustrates one of the hanger portions in perspective.

Figures 4 and 5 are views similar to Figure 2 with the hanger parts in other positions than shown in that figure, and

Figure 6 is similar to Figure 5 but showing another position of the hanger portions relative to each other.

In Figure 3 the upper of the two hanger portions is shown, it comprises a main portion for attachment to the window frame 1, this portion being denoted at 2. Extending from the top edge of said portion as part thereof is an inverted hook 3 to be known herein as a guide, or guide portion, this being arched and extended downwardly substantially parallel to the said body portion creating a narrow recess 3', thence extending downwardly and outwardly at an angle and terminating distant from said body 2.

Projecting from the lower edge of the body, preferably a part thereof, and lying beneath the guide 3 is a hook 4 as a support for a hanger

portion 5 secured to the sash 6 to be supported, said hook being upturned and at its extremity lies in slightly spaced relation to the terminus of the said guide 3 while extending slightly above the same and outward therefrom, being more distant from the body 2, therefore, than is the said terminal of said guide.

Struck up from the body portion 2, in this instance, is an upwardly directed hook 7 which lies between the guide and said hook 4 and directed toward the former, spaced from both, and lying vertically in line with them as seen in Figure 1.

The named portion 5 on the sash 6 has the usual eye or opening 5' in order that it may, of course, permit said portion to engage any one of the several described parts of the body portion.

It is particularly difficult, especially when working from within a room, to install a heavy sash particularly when the workman is required to reach far out in order to engage a sash hanger with a hook above. One of the objects herein is to obviate this difficulty and lighten the work.

That is to say, as shown in broken lines in Figure 2 the sash may be raised while in practically a vertical position and at once engaged upon the hook 4, the weight of the sash being directly imposed upon said hook at which time the worker is given a period of rest, if so desired, the downward slant of the hook 4 at this time preventing the sash from getting out of control. From such position the sash, when again lifted, will be engaged with and guided upwardly and inwardly as the hanger portion 5 meets said guide 3, the former reaching a position above the hook 7, whereupon in lowering the sash said portion 5 may be rested upon said hook as its seat, when the sash is in snug "home" position against the stops of the window frame.

Thus far described, the structure provided accommodates itself to situations where the portion 2 may be attached to the building at any required position or height above the window opening. However, sometimes the "trim" on a building due to its nearness to said window opening interferes with a chosen procedure in hanger practice. An advantage in the present structure, as providing for such a situation, may be seen by reference to Figure 6, wherein, as observed, that the distance from the window opening for the said portion, as compared to the former figures, is less than in said figures due to the necessary lowering of such portion 2, and since said portion is nearer to the seated sash

than before, the portion 5 may be directed upwardly by the guide 3 passes slidably into the recess 3' between said portion and said body and there remains without chance of lateral movement or shake. Thus the sash is as readily guided to its seat as in the first instance described without, however, being finally located on the hook 7. In removing the sash it may be handled so that its hanger portion 5 may be directly drawn from the recess and released from the hanger entirely. In regard to the lateral movement above mentioned it will be observed that the hanger portion 5 above the eye 5' is inclined at a slight angle to the balance thereof so that opposite portions about opposite walls of the recess 3'. This is an advantage in that when the sash is dismounted it is naturally swung outward. Therefore the angled portion assumes a vertical position and is at once free to drop away from said recess so that friction cannot retard ready removal. Again, this angular position more readily permits the hanger 5 to enter the narrow space between the extremities of the guide 3 and hook 4.

Sash hangers so far as is known, have had no provision for preventing a sash being dislodged and destroyed by winds when said sash has been inadvertently left unsecured at its lower extremity. In this regard attention is directed to the proximity of the free extremities of the guide 3 and the hook 4, and the fact that the former lies inward from the latter and slightly below it. In the event, therefore, the wind swings the freely suspended sash outwardly the top portion of the hanger 5, or that part above the eye 5' spans the space between the said extremities of said guide and hook as shown in broken lines in Fig. 5, preventing disastrous results.

In respect to the hook 7 it is to be stated that since it tends to hold the hanger 5 close to the window frame due to the downwardly and inwardly directed supporting edge thereof a safe position of the sash is assured even in light winds when said sash is hanging free, as when unlatched, and even if higher winds dislodge the sash from said hook 7, however, the member 5 will still be caught by the hook 4 and be safely held thereby.

I claim:

1. A sash hanger including in its construction a body for attachment in an upright position to a window frame, a hook extending from the lower portion of the body outwardly and upwardly therefrom on which to suspend a sash hanger portion, an outwardly and downwardly extending guide portion extending from the body, its terminus lying adjacent the terminal of the said hook, spaced therefrom, and lying between the same and said body, and a hook extending from the body from a position between the guide portion and the first named hook, and upwardly and outwardly extending toward said guide portion and terminating in spaced relation thereto, the terminal of the guide portion lying between both the named hooks.
2. A sash hanger including in its construction a body for attachment in an upright position to a window frame, a hook extending from the lower portion of the body outwardly and upwardly therefrom on which to suspend a sash hanger portion, a downwardly extending guide portion on and substantially paralleling the body a given distance and thence being outwardly extended downwardly at an angle and terminating between said body and the terminal of the named hook, and a hook extending outwardly and upwardly from the body from a position between the first named hook and said guide portion, and terminating in spaced relation to the terminal of each.
